CLAIM

The ornamental design for an earphone case, as shown and described.

DESCRIPTION

FIG. 1 is a front, bottom, right side perspective view of the new design for an earphone case;

FIG. 2 is a rear, top, left side perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top view thereof;

FIG. 8 is a bottom view thereof; and,

FIG. 9 is a front, bottom, right side perspective view thereof, illustrating that the earphone case is in an opened configuration.

The broken (dashed) lines show portions of the earphone case that form no part of the claimed design.

1 Claim, 9 Drawing Sheets
